PRODUCTION OF HYDROCARBONS

John Anderson and Robert C. Castner, Berkeley,
Calif., assignors to Shell Development Company,
San Francisco, Calif., a corporation of
Delaware

Application February 22, 1943, Serial No. 476,714

7 Claims. (Cl. 260—671)

This invention relates to the treatment of olefinic mixtures to produce higher boiling hydrocarbons. It deals particularly with the alkylation of hydrocarbons using such mixtures.

An important object of the invention is the provision of a more efficient and economical process for the production of alkylation products. Another object is to more efficiently utilize the different olefins of olefinic mixtures without having to resort to expensive preliminary fractionation of such mixtures. Still another object is to reduce the amount of reagents, particularly acid reagents, required for producing alkylation products. One specific embodiment of the invention has as a special object the production of isoparaffinic and aromatic hydrocarbon mixtures which are superior blending agents for aviation gasoline, particularly as regards power output of the gasoline under conditions of rich mixture operation. Still other objects and advantages of the invention will be apparent from the following detailed description of the new method of operation.

For the purpose of making the invention clear it will be described with more particular reference to its application to the treatment of butane-butylene fractions of petroleum cracking products. However, this application of the process is intended to be illustrative only and it will be understood that the invention is not limited with respect to either the nature or source of the olefins employed as starting materials.

Butane-butylene fractions are being used on a large scale for the production of blending agents for aviation motor fuels. These fractions are most widely used for alkylating isobutane in the presence of concentrated sulfuric acid as this procedure is more efficient and economical than any of the other available methods of producing high octane number motor fuels from such starting materials. It has been found, however, that not only can the quality of the product so obtained be further improved, but also the consumption of sulfuric acid in the process can be reduced, thus making the procedure even more economical. These advantages are obtained by carrying out the reaction of the isobutylene present in the starting material under conditions different from those used for conversion of the less reactive alpha and beta butylenes present therewith. The partial separation of these olefins by conventional fractionation methods is possible but quite expensive, while separation of isobutylene from alpha butylene in this manner is entirely impractical because of the small differences between their boiling points, and it is a feature of the invention in one of its preferred embodi-

ments that this separation is efficiently and economically effected by means of a reagent used in another step of the process and therefore without adding to the cost of operation. Thus, for the production of the highest yield of alkylation products of high power output, the isobutylene content of the starting fraction is used with benzene to produce tertiary butyl benzene while the secondary butylenes are reacted with isobutane to produce branched chain octanes, and sulfuric acid from the benzene treatment step is employed for separation of the butylenes prior to these reactions. For the purpose of illustrating the combination of steps characteristic of this procedure, the attached drawing shows, diagrammatically, a typical process flow.

Referring to the drawing, isobutane from any suitable source, for example, fractionation of natural gases or isomerization of normal butane, advantageously the normal butane recovered 20 from a later stage of the present process as hereinafter described, is introduced through line 1 to the first alkylation unit 2. This alkylation unit is preferably of the type described in United States Patent 2,232,674 comprising a closed circuit through which an emulsion of hydrocarbon and concentrated sulfuric acid under alkylating conditions is pumped. Secondary butylenes for reaction with the isobutane are fed to the first 30 alkylation unit by line 3 and the sulfuric acid necessary to maintain the concentration of the acid in the circulating emulsion at an effective value, preferably above 90%, is supplied by line 4. The products of reaction are withdrawn by line 5 to a separating zone 6 which may comprise settling, hydrocarbon neutralization and fractional distillation equipment in which the reacted emulsion is separated into an acid phase and a hydrocarbon phase; the latter is scrubbed with 40 caustic and fractionated into an isobutane fraction which, in case it contains substantial amounts of lighter gases, may be subjected to stripping for their removal, a normal butane fraction, and a higher boiling fraction of paraffinic 45 alkylation products which it may be desirable to further fractionate to separate a small amount of heavy ends which are undesirable in aviation gasoline. The isobutane fraction is returned to the alkylation unit by lines 7 and 3 to supply the 50 desired large excess of isobutane to olefin in the reaction, preferably at least 5 mols of isobutane per mol of olefin in the feed. The normal butane fraction is removed by line 8 and may be conducted to an isomerization unit, not shown, for conversion to isobutane for use in the process as previously indicated or may be dehydrogenated to 55 form olefins useful as feed to the first alkylation

unit or for the production of butadiene or other purposes. The paraffinic alkylation products which will be substantially branched chain paraffins of eight carbon atoms per molecule are removed by line 8 and used for blending with other products of the process as hereinafter described.

The withdrawn acid phase is separated into two parts, the major portion being returned to the first alkylation unit by line 10, while the remainder, an amount corresponding approximately to the fresh acid of higher concentration added by line 4, is divided into two portions which are fed by lines 11 and 12, respectively, to units 13 and 14. In unit 13, which may be one or more internally stirred mixers or a packed column or other suitable device for contacting immiscible liquids, the acid is intimately mixed with benzene introduced by line 15 at a temperature of about 20° C. to 50° C. for a period of about 5 to 15 minutes, preferably using about 0.1 to 0.25 volume of acid per volume of benzene. By this treatment undesirable components of the benzene, particularly sulfur-containing compounds such as thiophene, are removed and the final quality of the alkylation products of the process and the yield of such products per volume of starting acid are materially improved. The reacted emulsion is removed by line 16 to a separator 17 which is preferably a decantation vessel or the like wherein the treated benzene is separated and removed by line 18 and the acid is withdrawn by line 19. A part of the acid is returned to treater 13 by line 20 and the remainder, usually corresponding to about 20 to 50 pounds per barrel of benzene treated, is conducted to a dilution tank 21 which may also receive acid from line 22, as will be more fully explained hereinafter. In tank 21 the acid is diluted with sufficient water introduced by line 23 to reduce the concentration of the sulfuric acid to about 60% to 70%. The diluted acid is passed by line 25 to separator 26 where the impurities liberated by the dilution are permitted to accumulate as an upper layer which may be drawn off by line 27. Most preferably, the acid is cooled during dilution to maintain a temperature not greater than that employed in the benzene treatment step as this facilitates separation of impurities from the acid and reduces undesirable side reactions. The separation of the impurities may be further facilitated by intimately mixing the acid either in tank 21 or more preferably in separator 26 with a solvent for the impurities, advantageously liquefied normal butane from line 8 introduced by line 24. Evaporation of a part of such butane provides an efficient method of maintaining the acid at the desired low temperature. The diluted and at least partially purified acid is conducted by line 28 to an olefin absorption unit 29 which may advantageously be an apparatus of the type described in United States Patent 1,955,873, or of the type claimed in United States Patent 2,022,205, or of other suitable form. In the absorption unit the acid contacts a butane-isobutylene fraction containing isobutylene, normal butylenes and iso- and normal butane introduced by line 30. The acid and olefins are contacted under conditions preferably controlled so as to effect selective absorption of the bulk of the isobutylene with only relatively small absorption of normal olefins. The resulting mixture may be conducted to separator 32 by line 31 and the unabsorbed hydrocarbon containing the normal butylenes may be removed by line 33 and conducted to the first alkylation zone by line 3 for reaction with isobutane, as previously described. The acid,

containing the absorbed isobutylene, is fed by line 34 to a polymerization unit 35 in which it is brought to a temperature of about 70° C. to 110° C. in order to convert the isobutylene to polymers, mainly di-isobutylene. The polymerization of the absorbed olefin may advantageously be carried out in accordance with United States Patent 2,228,669, for example, using preferably normal butane supplied by lines 8 and 36 as the solvent for the polymer. Whichever method of polymerization is used, the reacted polymerization mixture may be withdrawn from polymerizer 35 by line 37 and fed to a separation unit 38 comprising the settling tanks, and hydrocarbon neutralizing and fractionating equipment suitable for separating the mixture into an acid phase and hydrocarbon streams comprising polymer of the desired boiling range for reaction with the previously mentioned pretreated benzene and lower and higher boiling hydrocarbons. The acid phase is removed by line 39 and for the most part returned by line 40 for further use in absorption and polymerization of the isobutylene while the remainder is removed from the system by line 41. Line 42 represents an outlet for n-butane and/or other undesired components of the hydrocarbon phase. The polymer produced is transferred by line 43 to the second alkylation unit of the system 44 which may be of the same type as, or different from, the first alkylation unit 2.

In the second alkylation unit 44 the polymer is contacted with pretreated benzene from separator 17, preferably caustic and water washed in units not shown, introduced by line 48. As catalyst for the reaction of the polymer with the benzene, sulfuric acid from line 12 is used. This acid is preferably diluted in tank 14 with water introduced by line 46 in an amount sufficient to reduce the acid concentration to between 80% and 90%, preferably about 85% and 88%, on a hydrocarbon-free basis. The diluted catalyst acid which may be stratified, extracted or otherwise treated to remove any impurities liberated by the dilution is admitted to the second alkylation unit by line 47. Most advantageously, the alkylation of the benzene by the polymer is carried out with a substantial molecular excess of benzene based upon the monomeric olefin equivalent of the polymer used, preferably at least four mols of benzene per mol of monomeric olefin in the polymer. When using di-isobutylene, for example, most preferably six to ten mols of benzene are used per mol of polymer while nine to fifteen mols are preferably used per mol of tri-isobutylene. The reaction temperature under these conditions is maintained between about 40° C. and 50° C., and a contact time of hydrocarbons with acid of about 20 to 30 minutes is preferably provided. A volume ratio of acid phase to hydrocarbon phase between 0.7 to 1 and 1.3 to 1 is advantageous. Under these preferred conditions substantially complete conversion of the polymer to tertiary butyl benzene may be obtained at atmospheric pressure but higher or lower pressure may be used if desired.

The reacted emulsion from the second alkylation unit is conducted by line 48 to separation zone 49 wherein the mixture is separated into an acid phase and a hydrocarbon phase and the latter is fractionated, preferably after treatment at above 100° C. with a base, advantageously with about 10% to 50% by volume of a caustic soda solution of 2% to 10% concentration at about 140° C. to 160° C. for about 10 to 30 minutes under superatmospheric pressure sufficient to

maintain the majority of the product in the liquid phase. The separated acid is withdrawn by line 58 and for the most part returned by line 51 to the alkylation unit. The remainder of the acid, approximately equivalent in amount to that introduced by line 47, is fed by line 22 to tank 21 as previously indicated. The separated excess benzene is removed by line 52 and a part is returned to the alkylation unit by lines 54 and 43 while the remainder is conducted by lines 53 and 15 to acid treater 13 to prevent the accumulation in the system of undesirable components. The aromatic alkylation products, together, if desired, with hydrocarbon diluents and/or a part of the excess unreacted benzene which may, if necessary, be later separated, are withdrawn by line 55 and fed, along with the paraffinic alkylation products from line 9, by line 56 to storage, represented by unit 57.

The following specific example illustrates the improved results, particularly with respect to increased yield of higher value aviation motor fuel obtainable by the process described in this invention. These results are based upon a charging stock of Dubbs cracking products having the following composition:

	Per cent
Propane	1
Isobutylene	18
Normal butylenes	29
Isobutane	12
Normal butane	40

The operating conditions for the different stages of treatment are as follows:

Isobutylene absorption in diluted isobutane alkylation acid from benzene treatment

H ₂ SO ₄ concentration in diluted acid	per cent
Acid to hydrocarbon ratio	0.1 to 1
Temperature	°C 20
Average time of contact	minutes 5

Polymerization of absorbed isobutylene

Average temperature	°C	39
Residence time in time tank	minutes	6
Mols isobutylene per mol H ₂ SO ₄	1.18	
Mols added butane per mol isobutylene	1.24	

Benzene pretreatment with isobutane alkylation acid

Titratable acidity of treating acid (as H ₂ SO ₄)	per cent	92
Total volumes of acid per volume of benzene	0.25 to 1	
Temperature	°C	35
Average time of treatment	minutes	10

Alkylation

	Of pretreated benzene with polymer	Of isobutane with residual butylene from polymer- ization
Concentration of sulfuric acid— Fed to reactor	percent	80
Withdrawn from reactor	do	79
Acid to hydrocarbon volume ratio in reactor	0.25 to 1	1 to 1
Average contact time in reactor	minutes	30
Average temperature	°C	50
Mols of benzene per mol of polymer in feed	9.8 to 1	20
Mols of isobutane per mol of olefin in feed	15 to 1	20

Under these operating conditions approximately

90% of the isobutylene and less than 5% of the secondary butylenes are removed in the absorption step. The residual olefinic hydrocarbon feed to the isobutane alkylation has the following composition:

	Per cent
Propane	1.2
Isobutylene	2.2
Normal butylene	33.6
Isobutane	14.5
Normal butane	48.5

In the polymerization step 98.8% of the absorbed isobutylene was removed from the acid giving a polymer containing 74.9% of di-isobutylene as feed to the benzene alkylation unit. The benzene pretreatment using benzene containing 0.47% sulfur as feed resulted in a reduction of the sulfur content to 0.06%. Alkylation of this benzene with the di-isobutylene gave an alkylation product containing 74.3% of tertiary butyl benzene, the remainder being mostly di-tertiary butyl benzene which may be recycled to the alkylation along with the excess benzene and unreacted di-isobutylene to obtain substantially quantitative production of the desired mono-tertiary butyl benzene or a yield of 233% by weight based on the isobutylene used. Recycling of the di-tertiary butyl benzene may, however, be omitted and this product separately recovered. From the alkylation of isobutane with the residual butylenes from the polymerization, a yield of alkylation products of 201% was obtained. These yields correspond to a total production of alkylation products equal to 175% by volume based on the olefins fed. When blended, in equal volumes, with 50% of an aviation base stock of 73 O. N. and tested, the allowable power output at rich mixtures of these alkylation products containing 3 cc. of lead tetraethyl is 1.33 times that of a corresponding blend of iso-octane (2,2,4-trimethyl pentane). A similar blend of the isoparaffinic alkylate only with an equal volume of the same base stock has an allowable power output at rich mixtures of only 1.08 times that of the iso-octane blend. Thus, the mixed aromatic isoparaffinic alkylation products of the invention are capable of producing a 23% increase in allowable power output over what would be obtained if the olefins were used exclusively for alkylation of isobutane.

The increased yield and quality of the alkylation products are obtained without any increase in sulfuric acid consumption since the acid from the isoparaffin alkylation is used in the other acid-consuming steps of the process. In view of the detrimental effect which organic impurities picked up during alkylation of isoparaffins with olefins have on the catalytic activity of sulfuric acid, it is surprising that the isoparaffin alkylation acid can thus be efficiently used for subsequent alkylations of aromatic hydrocarbons. It also could not have been predicted that such acid could be used for pretreatment of the benzene to be alkylated. This latter procedure is of advantage even when using different catalysts for the two alkylation operations. Thus, sulfuric acid from the isoparaffin alkylation step may be used first to treat benzene and then for the preparation of the polymers and the latter then reacted with benzene in the presence of a phosphoric acid catalyst. As an example of such operations, polymers identical with those described in the foregoing specific example were reacted with benzene which had been pretreated,

as described, in the presence of a solid phosphoric acid catalyst consisting of a calcined mixture of phosphoric acid and an absorbent clay. The operating conditions were as follows:

	Run number	
	1	2
Temperature..... ° C.	220-250	250-275
Pressure..... lbs.	250	250
Mol ratio benzene to polymer.....	10:1	10:1
Feed rate (grs. per liter of catalyst per hour).....	4,200	2,320

The products obtained had the following composition, expressed as mol percent of the total recovered hydrocarbon:

	Run number	
	1	2
Fraction boiling below 75° C.....	Per cent	Per cent
Di-isobutylene fraction.....	None	18
Tertiary butyl benzene fraction.....	46	14
Di-tertiary butyl benzene fraction.....	48	60
	6	8

When operating in this manner, the unreacted olefin, in this case di-isobutylene, is returned to alkylation unit 44 by lines 54 and 43 along with the recycled benzene so that substantially complete conversions are obtained. Instead of phosphoric acid, other alkylation catalysts such as hydrogen fluoride, aluminum chloride and the like may also be used, not only for the alkylation of the chosen aromatic hydrocarbon but also for the isoparaffin alkylation step and, most preferably, catalyst from the latter is used for effecting the former operation as previously indicated for the specific case employing sulfuric acid catalysts, such acid being supplemented, if necessary, with acid from another source.

Many other variations in the process may also be made; thus, instead of selectively absorbing the isobutylene in the isoparaffin alkylation acid prior to polymerization of the absorbed olefin, the polymerization may be carried out, either selectively or as a co-polymerization of the isobutylene with secondary butylenes or other olefins, in one step by contacting the olefin-containing hydrocarbon with such acid under polymerizing conditions as described, for example, in United States Patents 2,007,160 and 2,174,247. Alternatively, the polymerization step may be omitted entirely and preferably, using acid having the same concentration as that used for the second alkylation, the olefin may be absorbed in the acid as previously described and the absorption product from line 34 connected directly to unit 44 for alkylation of the benzene. Tertiary butyl benzene, for example, may be thus produced in very good yield. It is sometimes advantageous to add other olefins during the second alkylation step. Thus, propylene may be added along with the isobutylene polymers and/or absorption products, and it has been found that the mixtures of cumene and tertiary butyl benzene are fully equal to the products from alkylating benzene with isobutylene as far as their blending value in aviation gasoline is concerned. Furthermore, their vapor pressure is such that larger amounts can be successfully included in the final gasoline without exceeding current distillation specifications. In fact, the process of the invention offers many advantages

when propylene is used alone in the second alkylation step of the process for, although it is not practicable to carry out isoparaffin alkylations with propylene in the presence of sulfuric acid

- 5 which has been employed for the alkylation of an isoparaffin with other olefins, such acid is quite suitable for the alkylation of aromatic hydrocarbons with propylene. An especially advantageous method of operation is to alkylate 10 isobutane in the first alkylation stage with one or more butylenes which may, if desired, be admixed with propylene, and then carry out the alkylation of the aromatic hydrocarbon with propylene in the presence of catalyst from the isobutane alkylation. Particularly when the alkylation of the aromatic hydrocarbon is carried out with an olefin or olefins directly, that is, without previous absorption and/or polymerization treatment, it is advantageous to employ the residual unreacted olefins, after fractionation to separate alkylation products, and normal paraffins or other undesired components if necessary, as feed for the isoparaffin alkylation step of the process. This method of operation is especially useful when the alkylation of aromatic hydrocarbons in unit 44 is effected in the vapor phase with olefins having four or more carbon atoms per molecule, while liquid phase alkylation methods are used for the isoparaffin alkylation in unit 2. It will be understood that, where isobutane alkylation has been referred to in the foregoing as being effected in a single unit represented in the drawing by unit 2, such alkylation may comprise a plurality of reaction stages in which the isobutane or other isoparaffin or isoparaffins are alkylated with the same or different olefins using fresh catalyst for each of the alkylations, or more preferably adding such catalyst to one or more such stages 30 only and carrying out the other isoparaffin alkylation stage or stages with catalyst which has been employed in the earlier alkylations. Thus, for example, when using sulfuric acid as the catalyst, isobutane may be alkylated with a butylene or with a butylene-propylene mixture while maintaining the desired catalyst concentration by adding fresh acid, and in another stage isobutane may be alkylated by reaction with amylanes in the presence of acid withdrawn 35 from the butylene alkylation reaction. It will also be understood that in these alkylation stages or in any of the other operations of the process it may be desirable to supplement or even in some cases to replace the acid or other catalyst 40 from the preceding units with fresh catalyst in the later reactions. The isobutane may alternatively be alkylated with polymer obtained by treatment of an olefin-containing hydrocarbon mixture with the used liquid inorganic acid catalyst from alkylation of benzene with an olefin 45 as previously described.
- Not only may the process be carried out with other olefins than those of three to five carbon atoms or polymers thereof previously described 50 by way of example but also either or both of the reactions in units 2 and 44 may be effected directly with olefins or with other alkylating agents. Thus, in addition to absorption products 55 of olefins in sulfuric or other suitable acids, esters, either of organic or inorganic acids, as propyl, butyl or amyl, or higher alkyl sulfates, phosphates, borates, chlorides, formates, acetates and the like, or ethers or alcohols may be used.
- 60 Instead of isobutane, isopentane, isohexane, 2,3-

dimethyl butane and other isoparaffins having a tertiary carbon atom may be employed in the first alkylation stage while toluene, the xylenes, ethyl benzene, propyl or isopropyl benzene, mesitylene, cymene, naphthalene or other aromatic hydrocarbons may be used in place of or along with benzene in the process, although when the aromatic alkylation product is intended for use in motor fuels volatility considerations make it advantageous to use lower boiling aromatic hydrocarbons, particularly benzene or toluene. It will thus be seen that the invention is applicable to the treatment of a wide variety of starting materials and is not limited to the details of operation and reaction conditions described by way of example, nor by any theory suggested in explanation of the improved results which are obtained.

We claim as our invention:

1. A process for producing motor fuel components of high anti-knock value which comprises reacting isobutane with a normal butylene in the presence of concentrated sulfuric acid, separating the resulting alkylation products from the used acid, subjecting benzene to the action of the used acid to remove undesirable impurities, separating the purified benzene from the acid, contacting the latter with a hydrocarbon mixture containing isobutylene and a normal butylene to separate at least a part of the isobutylene content from said normal butylene, alkylating the purified benzene with the thus separated isobutylene in the presence of a catalyst comprising used sulfuric acid from the isobutane alkylation, and feeding said separated normal butylene to the isobutane alkylation.

2. A process for producing motor fuel components of high anti-knock value which comprises reacting isobutane with a normal butylene in the presence of concentrated sulfuric acid, separating the resulting alkylation products from the used acid, subjecting a hydrocarbon mixture containing isobutylene and a normal butylene to contact with at least a part of the used acid to separate isobutylene therefrom, alkylating benzene with the separated isobutylene in the presence of used sulfuric acid from the isobutane alkylation, and feeding remaining normal butylene to said isobutane alkylation.

3. A process for producing isoparaffins and alkylated aromatic hydrocarbons which comprises reacting an isoparaffin with a secondary olefin in the presence of concentrated sulfuric acid, separating the resulting alkylation products from the used acid, subjecting a hydrocarbon mixture containing secondary and tertiary olefins to contact with at least a part of the used acid to separate the tertiary olefin therefrom, alkylating an aromatic hydrocarbon with the thus separated olefin in the presence of used sulfuric acid from the isoparaffin alkylation, and feeding remaining secondary olefin to said isoparaffin alkylation.

4. A process for producing isoparaffins and

alkylated aromatic hydrocarbons which comprises reacting an isoparaffin with a secondary olefin in the presence of an inorganic acid alkylation catalyst, separating the resulting alkylation products from the used acid, subjecting a hydrocarbon mixture containing secondary and tertiary olefins to contact with at least a part of the used acid to separate the tertiary olefin therefrom, alkylating an aromatic hydrocarbon with the thus separated olefin in the presence of used acid from the isoparaffin alkylation, and feeding remaining secondary olefin to said isoparaffin alkylation.

5. A process for producing isoparaffins and alkylated aromatic hydrocarbons which comprises reacting an isoparaffin with a secondary olefin in the presence of concentrated sulfuric acid, separating the resulting alkylation products from the used acid, subjecting an aromatic hydrocarbon to the action of the used acid to remove undesirable impurities, separating the purified aromatic hydrocarbon from the acid, contacting a hydrocarbon mixture containing secondary and tertiary olefins with used acid from the isoparaffin alkylation to separate the tertiary olefin therefrom, alkylating the purified aromatic hydrocarbon with the thus separated olefin in the presence of used sulfuric acid from the isoparaffin alkylation, and feeding remaining secondary olefin to said isoparaffin alkylation.

6. A process for producing isoparaffins and alkylated aromatic hydrocarbons which comprises reacting an isoparaffin with a secondary olefin in the presence of concentrated sulfuric acid, separating the resulting alkylation products from the used acid, subjecting an aromatic hydrocarbon to the action of the used acid to remove undesirable impurities, separating the purified aromatic hydrocarbon from the acid, contacting the latter with a hydrocarbon mixture containing

secondary and tertiary olefins to separate the tertiary olefin therefrom, alkylating the purified aromatic hydrocarbon with the thus separated olefin in the presence of used sulfuric acid from the isoparaffin alkylation, and feeding remaining secondary olefin to said isoparaffin alkylation.

7. A process for producing isoparaffins and alkylated aromatic hydrocarbons which comprises reacting an isoparaffin with a secondary olefin in the presence of an inorganic acid alkylation catalyst, separating the resulting alkylation products from the used acid, subjecting an aromatic hydrocarbon to the action of the used acid to remove undesirable impurities, separating the purified aromatic hydrocarbon from the acid, contacting the latter with a hydrocarbon mixture containing secondary and tertiary olefins to separate the tertiary olefin therefrom, alkylating the purified aromatic hydrocarbon with the thus separated olefin in the presence of used acid from the isoparaffin alkylation, and feeding remaining secondary olefin to said isoparaffin alkylation.
